REFRIGERATOR CABINET

Chan Fook Leng, 56 Tras St., Singapore

Filed Feb. 24, 1966, Ser. No. 1,167

Term of patent 14 years

(Cl. D67—3)

Fig. 1.

Fig. 2.

Fig. 3.

Fig. 4.

Fig. 5.

Fig. 6.

Fig. 7.

Fig. 8.

FIGURE 1 is a front perspective view of the refrigerator cabinet showing my new design, the shelves being in an extended position;

FIGURE 2 is a front elevational view thereof;

FIGURE 3 is a rear elevational view thereof;

FIGURE 4 is a top plan view thereof;

FIGURE 5 is an elevational view taken from the right end of FIGURE 2;

FIGURE 6 is an elevational view taken from the left end of FIGURE 2;

FIGURE 7 is another front elevational view thereof, the shelves being in a retracted position; and

FIGURE 8 is a top plan view of FIGURE 7.

The dominant features of my design reside in the portions shown in full lines.

I claim:

The ornamental design for the refrigerator cabinet, as shown and described.
